DESIGN FOR A TRIMMING

Abraham Bloom, Chicago, Ill.

Application May 14, 1943, Serial No. 110,211

Term of patent 3½ years

To all whom it may concern:

Be it known that I, Abraham Bloom, a citizen of the United States of America and a resident of Chicago, in the county of Cook and State of Illinois, have invented a new, original, and ornamental Design for a Trimming, of which the following is a specification, reference being had to the accompanying drawing, forming a part thereof.

Fig. 1 is a plan view showing my new design for a Trimming.

Fig. 2 is a transverse section taken on a larger scale than Fig. 1 and substantially as indicated at line 2—2 on Fig. 1.

The back of the design is plain.

I claim:

The ornamental design for a trimming, substantially as shown and described.

ABRAHAM BLOOM.
